INDEX DEVICE

Conrad Veit, Detroit, Mich.

Application February 21, 1936, Serial No. 65,031

3 Claims. (Cl. 129—16.8)

This invention relates to index devices and the object of the invention is to provide an index device attachable to a marginal portion of a card or folder to contain a removable insert strip and having a signal slidably mounted on the upper edge thereof and movable to position over different indications on the insert strip.

Another object of the invention is to provide a return bent transparent strip arranged to be secured to the upper edge of a card or folder and formed to provide a bead at the return bent edge and a signal being slidably mounted on said bead to be moved longitudinally thereof.

Another object of the invention is to provide a return bent transparent strip having one side longer than the other, the longer side being secured to the card and the shorter side being arranged for the insertion of a removable insert strip therebeneath and the signal being slidably mounted on the return bent edge of the index strip and movable to alignment with different indications on the insert strip to act as a signal in connection therewith.

A further object of the invention is to provide a return bent transparent Celluloid strip attachable to the upper edge of a card or file and formed to provide a bead at the return bend extending longitudinally of the upper edge of the card and a signal slidably mounted on the said bead, said signal being C-shaped in cross section to closely fit the bead and prevent its removal therefrom and being of a contrasting color so as to be readily seen in a file drawer.

These objects and the several novel features of the invention are hereinafter more fully described and claimed and the preferred form of construction by which these objects are attained is shown in the accompanying drawing in which—

Fig. 1 is a perspective view showing my index device attached to the upper edge of a folder or card.

Fig. 2 is an enlarged section taken on line 2—2 of Fig. 1.

Fig. 3 is an enlarged section taken on line 3—3 of Fig. 1.

The card 1 may be an index card or the side of a folder to which my index device may be attached. A return bent transparent strip is fitted over the upper edge of the card 1 and is formed to provide an enlarged bead 2 at the return bend and having a flange 3 extending over one side of the card and a transparent flange portion 4 extending over the opposite side thereof. The portion 3 is slightly longer than the portion 4 and is attached to the card by means of wire

staples or stitches 5 at spaced intervals as shown in Fig. 1. These wire stitches 5 on the front of the card come just below the free flange 4 of the transparent strip. The return bent transparent strip is resilient in nature and the lower edge of the flange 4 may be lifted away from the face of the card to allow an insert strip 6 to be inserted beneath this flange 4 so that the lower edge of the insert strip 6 rests on the extending portions of the wire securing members 5. When the flange 4 is released it will spring inwardly against the face of the insert strip 6 and over the upper edge of the wire stitches 5 to hold the insert strip in place supported on said wire stitches 5.

A signal 7 is provided which is C-shaped in cross section as shown in Figs. 1 and 3 and this signal is slipped over the end of the bead 2 and may be moved longitudinally of said bead to any desired point thereon. The signal 7 is preferably of a contrasting color so as to be readily seen and in the form of the device shown in Figs. 1 and 3 this signal 7 may be moved to position over any of the month indications on the insert strip 6 shown in Fig. 1. The signal 7 is preferably formed so as to clamp firmly about the bead 2 so that a slight pressure of the fingers is required to move the signal longitudinally of the bead 2 and thus prevent the signal from being accidentally moved. In using monthly indications on the insert strip 6 as shown in Fig. 1 the signal may be moved to any desired month and by looking over the cards in the file all the cards may be readily picked out in which the signal is positioned over any particular month. Thus, by sighting longitudinally down the file, all of the cards having a signal over (September, for instance) may be readily seen and as the visible signal is the highest point on the card the signals stand out very clearly.

While I have shown monthly indications on the insert strip, it will be understood that any indications desired may be provided on this insert strip and the signal 7 may be moved to any point desired in relation thereto. It is also possible to provide several signals 7 of different colors on the bead 2 to provide several different indications on each card.

From the foregoing description it becomes evident that the device is very simple and efficient in operation, may be quickly and easily applied to a card, will allow the signals to be moved quickly and easily to any point on the transparent bead and provides a device which accomplishes the objects described.

Having thus fully described my invention, its utility and mode of operation, what I claim and desire to secure by Letters Patent of the United States is—

- 5 1. An index device comprising a card, a return bent transparent strip secured over the upper edge of the card, one side of the strip being longer than the other, a series of wire stitches extending through the longer side of the transparent strip and through the card, an insert strip inserted beneath the free side of the transparent strip and exposed to view therethrough, the lower edge of the insert strip resting on the wire stitches.
- 10 2. An index device comprising a card, a return bent transparent strip secured over the upper edge of the card, one side of the strip being longer than the other, a series of wire stitches extending through the longer side of the transparent strip and through the card, an insert strip inserted beneath the free side of the transparent strip and exposed to view therethrough, the lower edge of the insert strip resting on the wire stitches, the return bent transparent strip being provided with a resilient bead at the return

bend exerting a tension on the shorter side of the strip to hold the insert strip from movement longitudinally of the transparent strip and a signal slidable longitudinally of the bead and arranged to register with indications on the insert strip. 5

- 15 3. An index device comprising a card, a return bent transparent strip secured over the upper edge of the card and having a longitudinal bead formed in the return bend, the strip being of resilient material, one side of the strip being longer than the other, a series of wire stitches extending through the longer side of the transparent strip and through the card, the free side of the transparent strip terminating above the wire stitches, an insert strip inserted beneath the free side of the transparent strip and resting on the wire stitches, said longitudinal resilient bead urging the free side of the transparent strip toward the card to retain the insert strip from displacement longitudinally and a C-shaped signal slidable on the bead and registrable with indications on the insert strip while held in position by the free side of the transparent strip. 20
